WEARING APPAREL

Margaret H. Wittenberg, Millburn, N. J., assignor
to Jantzen Knitting Mills, New York, N. Y., a
corporation

Application July 9, 1945, Serial No. 603,844

6 Claims. (Cl. 2—42)

1

The present invention relates to wearing apparel and more particularly to a brassière-bandeau garment.

The primary object of the present invention is to provide a brassière-bandeau which is well adapted to be worn as a sun-bra and which is so constructed that it provides adequate support for the bust and also satisfies the requirements of modesty.

Another object of the invention is to provide a brassière-bandeau having outer and inner front parts and back portions which are common to both of said parts, thus eliminating relatively displaceable back portions which might otherwise detract from the appearance of the garment.

Another object of the invention provides a brassière-bandeau having inner and outer front parts detachably secured to each other at the sides of the garment. More specifically, in accordance with this object of the invention, the garment can be constructed so that the parts which provide the bust support can be worn as a brassière or the garment can be constructed so that the part which provides the bust support can be detached from the other part, leaving a complete article of wearing apparel which can be worn as the top of a playsuit or sun-garment.

The above and other objects, features and advantages of the invention will be fully understood from the following description considered in connection with the accompanying illustrative drawings.

In the drawings:

Fig. 1 is a perspective view of the brassière-bandeau embodying the present invention, illustrating the garment as it appears on the wearer;

Fig. 2 is a view of the back of the brassière-bandeau at it appears on the wearer;

Fig. 3 is a view similar to Fig. 1 showing the portions of the outer front part of the brassière-bandeau folded back, for the purpose of illustration of the construction of the garment;

Fig. 4 is a detailed sectional view of the line 4—4 of Fig. 3;

Fig. 5 is a front perspective view of another form of brassière-bandeau embodying the present invention;

Fig. 6 is a view similar to Fig. 5 showing the portions of the outer front part removed from the other part of the brassière-bandeau;

Fig. 7 is a front perspective view of another form of a brassière-bandeau embodying the present invention;

2

Fig. 8 is a view similar to Fig. 7 illustrating the detachability of the bust support.

Referring now to the drawings in detail and first to the form of the invention illustrated in Figs. 1 to 4, the brassière-bandeau constructed in accordance with the present invention comprises a body encircling member having an inner front part 10 which forms a bust support and which as here shown is of a type having breast pockets or bust cup 12. Bands 14 extend from the opposite ends of the inner front part 10 and are provided with any suitable fastening means 15 for detachable and adjustable securement at the back of the wearer. Said body encircling member 15 has a front part which is larger than the inner front part or bust support 10 so as to cover and conceal the latter when the brassière-bandeau is on the wearer and to provide more body coverage than is afforded by the inner front part of bust support 10. Front part 16 comprises, as here shown, the portions 18 which are secured in the garment by stitching 20 at the outer side edges, the bust cups 12, respectively. Front portions 18 extend forwardly from the seams 20 at the opposite sides of the garment to lie over and cover the breast pockets 12. Each of said front portions 18 is approximately triangular in shape as illustrated in Fig. 3. Said front portions are separable from each other and are elongated laterally of the wearer and of reduced width at their respective free end portions 22 whereby said free end portions can be conveniently tied together for securing the front portions 18 in position over the bust-support 10 and to provide an ornamental bow 24 as illustrated in Fig. 1. Thus it will be understood that in the brassière-bandeau the bust support 10 can be fastened in position with the desired degree of tightness in accordance with the wearer's preference and that the front part 16 can be arranged with the desired degree of looseness in accordance with the wearer's preference without interfering with the desired tightness of the body encircling member around the wearer. Front portions 18 may be cut and stitched as indicated at 31 to provide a rounded fullness at the breasts of the wearer.

The upper pointed ends 26 of the portions 18 of the outer front part 16 are detachably secured in any suitable way as by adjustable buckles 28 to companion shoulder straps 30 which are stitched, as indicated at 32 in Fig. 2, or otherwise secured at their lower ends to the companion bands 14 which constitute the back part of the body encircling member. The upper pointed ends

34 of the breast pockets 12 of the bust support are adjustably secured to the upper pointed end portions 26 of outer front portions 18 in any suitable way as by adjustable buckled straps 36. Thus, laterally spaced upper edge portions of inner front part 10 are adjustably secured to upper edge portions of outer front part 16 so that the breast pockets 12 can be properly positioned without interference by the outer front part 16 of the garment.

Referring now to the form of the invention illustrated in Figs. 5 and 6, the brassière-bandeau is constructed so that the outer front part 16A comprising the companion portions 18A is detachable from the inner front part or bust support 10A. This detachable feature can be provided by any suitable means which as here shown is constituted by buttons 38 on part 10A and by button-holes 40 on portions 18A of the outer front part 16A. It will be understood that any other separable fasteners, for example hooks and eyes, snap fasteners, slide fasteners or zippers, etc., can be used instead of the buttons and button holes on the companion detachable parts. In this form of the invention, the shoulder straps 30A are arranged to be fastened to the upper pointed ends 34A of the breast pockets 12A of part 10A. Preferably the front ends of shoulder straps are detachably and adjustably secured to the upper ends of breast pockets 12A in any suitable way as by the adjustable and fastening devices 36A. Detachable and adjustable fastening devices suitable for this purpose are well known in the apparel art and therefore require no further description. The upper pointed ends 26A of front portions 18A of the outer front part 16A are detachably secured to the front ends of shoulder straps 30A in any suitable way for example by providing said shoulder straps with buttons 42 and by providing upper pointed end portions of portions 18A with button holes 44. Portions 18A are tieable together at their outer end portions 22A of reduced width for securing said front portions in position and for forming a bow 24A as illustrated in Fig. 5. It will be understood that the part 16A is provided with bands 14A, one of which is shown in Fig. 5, and that the two bands are detachably and adjustably secured together at the back of the wearer substantially in the same way as illustrated in Fig. 2. Also it will be understood that the shoulder straps 30A are secured to the companion bands 14A substantially in the same way as illustrated in Fig. 2. If desired, the shoulder straps 30 or the shoulder straps 30A can be provided with adjustable portions at the lower rear ends thereof for adjustment of said shoulder straps. It will be noted that the front portions 18A of the garment illustrated in Figs. 5 and 6 are sufficiently large to conceal the bust support and to provide greater body coverage than is provided by said bust support. In short, it will be noted that the garment illustrated in Figs. 5 and 6 is substantially the same as the garment illustrated in Figs. 1 and 2 and in addition provides for the removal of the front part 16A so that the other part of the garment can be worn without said front outer part 16A either as an ordinary brassière or as part of a playsuit.

In the form of the invention illustrated in Figs. 7 and 8, the brassière-bandeau instead of being constructed to provide for the detachment of the front outer part from the bust support is constructed to provide for the detachment of the

bust support from the garment. Thus, as here shown, the bust support 10B is constituted by the inner front part and is detachably secured at its opposite ends to the adjacent end portions 46, respectively, of the bands 14B which are stitched to the companion front portions 18B of the outer front part 16B of the garment. It will be noted that the front end portions 46 of the bands 14B are disposed inwardly of the adjacent front portions 18B for securing the opposite ends of bust support 10B to the garment. End portions 46 of bands 14B are provided as here shown with buttons 38B and the ends of bust support 10B are provided with button holes 40B. The upper pointed ends 34B of the breast pockets 12B of the bust support are provided with looped straps 46 detachably engageable with the hooked ends 48 of adjustable buckles 50 carried by straps 52 which are stitched to the upper pointed ends 26B of the companion front portions 18B. In this form of the invention, a halter strap 54 is provided instead of the shoulder straps 30 and 30A, the ends of said halter strap being adjustably secured to the pointed upper ends 26B of the front portions 18B of the outer part of the garment. It will be noted that front portion 18B of the outer part 16B are large enough to conceal the bust support 10B and to provide greater body coverage than is afforded by the bust support. Also it will be understood that the bust support can be detached from the garment so that the latter can be worn if desired without said bust support 10B, in which case the front portions 18B can be fastened together at the front 35 of the wearer with the desired degree of tightness on the body of the wearer and also to form the ornamental bow 20B.

It will be noted that in each of the forms of the invention the bands which are positioned at 40 the back of the wearer are common to the inner and outer parts of the garment thus making it unnecessary to provide both parts of the garments with back portions and thus also improving the appearance of the garment on the wearer. Further, it will be observed that the brassière-bandeau of the present invention is constructed in each form thereof so that the bust support can be adjusted to suit the preference of the wearer without interference by the outer front part of the garment. It will be noted also that the end portions 22 (or 22A or 22B) of the front part of the garment can be tied together independently of the bust support or said end portions can be tied together around the narrow portion 13 between the breast pockets 12.

It will be understood that the invention may be embodied in various forms other than those herein specifically illustrated or described and that in the illustrated forms certain changes in 60 the details of the construction and in the arrangement of parts may be made without departing from the principles or underlying idea of the invention within the scope of the appended claims.

Having thus described my invention, what I 65 claim and desire to secure by Letters Patent is:

1. A garment comprising a body encircling member having a bust supporting part and outer front portions extending forwardly from the opposite sides of the garment to lie over the bust 70 supporting part in movable relation thereto, said front portions being separable from each other and constructed and arranged to be attached to each other at their adjacent ends, said bust supporting part comprising breast pockets, and means 75 adjustably securing the upper edge portions of

said breast pockets to upper edge portions, respectively, of said outer front portions, said front portions being detachable from said body encircling member.

2. A garment comprising a body encircling member having a bust supporting part and outer front portions extending forwardly from the opposite sides of the garment to lie over the bust supporting part in movable relation thereto, said front portions being separable from each other and constructed and arranged to be attached to each other at their adjacent ends, said bust supporting part comprising breast pockets, said bust supporting part being detachably connected at its opposite ends in said body encircling member, and means connected to laterally spaced points adjacent upper front edge of the body encircling member for holding the latter against downward movement on the wearer.

3. A brassière-bandeau garment, comprising a pair of bust cups and means to hold the same in position on the wearer, and a pair of covering bands positioned entirely externally of said bust cups, and attached thereto respectively, only at the outer side edges thereof, said bands being distinct from each other and from said bust cups and extending directly toward each other in a horizontal direction at the front of the garment from said side edges, respectively, of the bust cups and being of sufficient length and width to cover the latter, said bands being movable in relation to each other and to said bust cups and terminating in free end portions adjustably attachable to each other for releasably holding said bands in position over said bust cups in covering relation thereto.

4. A brassière-bandeau garment, comprising a pair of bust cups and means to hold the same in position on the wearer, and a pair of covering bands positioned entirely externally of said bust cups, and attached thereto respectively, only at the outer side edges thereof, said bands being distinct from each other and from said bust cups and extending directly toward each other in a horizontal direction at the front of the garment from said side edges, respectively, of the bust cups and being of sufficient length and width to cover the latter, said bands being movable in relation to each other and to said bust cups and terminating in free end portions attachable to each other at the front of the garment centrally between the bust cups for releasably holding said bands in position over said bust cups in covering relation thereto.

5. A brassière-bandeau garment, comprising a pair of bust cups and means to hold the same in

position on the wearer, said holding means including shoulder strap parts and a back strap, and a pair of covering bands positioned entirely externally of said bust cups, and attached thereto respectively, only at the outer side edges thereof, said bands being distinct from each other and from said bust cups and extending directly toward each other in a horizontal direction at the front of the garment from said side edges, respectively, of the bust cups and being of sufficient length and width to cover the latter, said bands being movable in relation to each other and to said bust cups and terminating in free end portions adjustably attachable to each other for releasably holding said bands in position over said bust cups in covering relation thereto, said covering bands having upper portions attached to said shoulder strap parts, respectively, above said bust cups.

6. A brassière-bandeau garment, comprising a pair of bust cups and means to hold the same in position on the wearer, said holding means including shoulder strap parts and a back strap, and a pair of covering bands positioned entirely externally of said bust cups, and attached thereto respectively, only at the outer side edges thereof, said bands being distinct from each other and from said bust cups and extending directly toward each other in a horizontal direction at the front of the garment from said side edges, respectively, of the bust cups and being of sufficient length and width to cover the latter, said bands being movable in relation to each other and to said bust cups and terminating in free end portions adjustably attachable to each other for releasably holding said bands in position over said bust cups in covering relation thereto, and means for adjustably securing said covering bands to said shoulder strap parts, respectively.
